COMBINATION GUARD AND HEAT TRANSFER DEVICE

Charles W. Hartwig, Hastings-on-Hudson, N. Y.

Application April 20, 1933. Serial No. 666,953

6 Claims. (Cl. 257—262)

This invention relates to a combination guard and heat radiator for use on a heated pipe of a house-heating system, or the like.

It is an object of the invention to provide a simple and inexpensive device capable of being snapped on or off a pipe, for providing additional heating surface and for preventing physical injury to a person coming in contact with the same.

Other objects and advantages will be apparent from the following description taken in connection with the accompanying drawing, wherein

Fig. 1 is a perspective illustrating one application of the invention, and

Fig. 2 is a top plan view.

Referring to the drawing, a pipe 10 is adapted to have hot water, steam, or other fluid, either hot or cold pass therethrough, such pipe forming a part of a heating or refrigerating system. In small rooms, such as bath rooms and the like, pipes extend through the room and such pipes are relied upon for heating the room without the ordinary type of radiator. These pipes are oftentimes quite hot and cause painful burns to persons using such room when they accidentally come in contact with such pipes. Further the rooms are inadequately heated due to the small amount of heat-radiating surface. In order to overcome these objectionable features, the pipe 10 is provided with a number of heat-radiating fins 11 formed by a copper sheet bent to produce undulations or corrugations having flat sides connected at their inner and outer edges by means of substantially right angle bends, the inner group of which lie flat against a curved cooperating plate 12 as shown.

The above described construction is of such a character that it is flexible, and the inner plate forms substantially two-thirds of a cylinder so that the heat-radiating fin assembly can be easily snapped onto the pipe 10, or removed therefrom. As shown the lateral extremities of the corrugated outer fin member and the curved inner fin member are bent around to form cooperating loops 13 and 14 respectively, permitting the cooperating fin members to be moved endwise relative to each other in order to separate them or assemble them.

Although for purpose of illustration only a short section of a fin assembly is shown, it is intended that the fin assembly be produced in lengths of any desired size depending upon the various factors of place and use.

The fins may be perforated especially where the device is desired to be used only as a guard.

It will be apparent to those skilled in the art

that various other changes may be made in the construction and arrangement without departing from the spirit of the invention, and therefore the invention is not limited to that which is described in the specification and shown in the drawing, but only as indicated in the appended claims.

What is claimed is:

1. A combination guard and heat transfer device adapted to be applied upon a pipe and comprising a curved inner plate for directly conforming to and engaging said pipe, and a second curved plate fitted to the first plate and having its ends interlocked therewith to form a unitary structure, said cooperating sections being of a size to snap on a pipe, said outer section having a plurality of outwardly extending folds of a uniform size, and providing longitudinal air passages and increased heat transfer surface, the outer portions of said folds being flat and forming a substantially annular guard. 65

2. A combination guard and heat transfer device adapted to be applied upon a pipe and comprising a curved inner plate for directly conforming to and engaging said pipe, and a second curved plate fitted to the first plate and having its ends interlocked therewith to form a unitary structure, said cooperating sections being of a size to snap on a pipe. 80

3. A combination guard and heat transfer device adapted to be applied upon a pipe and comprising a cylindrically curved plate adapted to snugly engage a pipe upon which the device is applied, and a cooperating corrugated member snugly engaging the cylindrical plate and having its ends interlocked therewith. 85

4. A combination guard and heat transfer device adapted to be applied upon a pipe and comprising a plate for directly conforming to and engaging said pipe, and a second plate fitted to the first plate and having its ends interlocked therewith to form a unitary structure made up of cooperating sections, said cooperating sections being of a size to snap on a pipe, said second plate having a plurality of outwardly extending folds. 95

5. A combination guard and heat transfer device constructed for application upon a pipe for providing heat transfer and comprising a member for directly engaging the pipe upon which the device is to be applied, and a second member cooperatively associated with the first member and having portions in intimate heat exchange relation with the first member and having other portions folded outwardly to provide increased heat exchange surface, said members being as- 105 110

sembled in a manner to provide a unitary structure, said device being constructed to snap on and clamp onto a pipe.

6. A combination guard and heat transfer device constructed for application upon a pipe or the like for providing heat transfer, and comprising a body formed to provide direct heat

transfer by conduction between the pipe and body, said body having outwardly extending folds to provide increased heat exchange surface, and also being constructed to snap on and clamp onto a pipe.
